[57] CLAIM

The ornamental design of a paper bundling table, substantially as shown and described.

DESCRIPTION

FIG. 1 is a perspective view of a paper bundling table showing my design;

FIG. 2 is a right elevational view of the same;

FIG. 3 is a front elevational view of the same;

FIG. 4 is a top plan view of the same;

FIG. 5 is a left elevational view of the same;

FIG. 6 is a rear elevational view of the same;

FIG. 7 is a bottom plan view of the same;

FIG. 8 is a perspective view of the table wherein the cover has been removed for convenience of illustration; and

FIG. 9 is a plan view of the table looking in the direction of the arrows 9—9 on FIG. 8.
